BUILDING DIRECTORY

Application filed July 28, 1930. Serial No. 471,262.

This invention relates to card picture and sign exhibits and more particularly to a directory of the type placed in the entrance halls or lobbies of buildings. It is to be understood that the device may be used as a building directory or as a sign in a store or theater lobby or for any other purpose for which it may be found suitable.

One object of the invention is to provide a display device of this character consisting of a frame adapted to be supported upon a wall and carry display elements to which the names of tenants of the building and numbers of the rooms occupied by them. 10 Another object of the invention is to provide this directory with name-carrying elements which are individually removable from the frame so that the names may be applied to them before they are fitted into the frame, 20 thereby making it possible to easily insert the names of new tenants in the directory.

Another object of the invention is to permit the name-carrying elements or bars to be shifted vertically in the frame and thereby permit a bar carrying the name of a new tenant to be very easily set in the sign in its proper position with respect to other names already in place.

Another object of the invention is to so mount the name-carrying bars that, while they may be easily set in place and shifted vertically of the frame when in place, they will not slip out of position when a transparent closure for the front of the frame is moved to an opened position.

The invention is illustrated in the accompanying drawings, wherein.

Figure 1 is a perspective view of the improved directory,

Fig. 2 is a transverse sectional view taken on the line 2-2 of Fig. 1,

Fig. 3 is a sectional view taken vertically through the directory,

Fig. 4 is a sectional view taken transversely through one of the name-carrying bars on the line 4-4 of Fig. 1, and

Fig. 5 is a perspective view illustrating a modified construction.

This improved building directory is intended to be mounted upon a wall or other

support in an entrance hall or lobby and has a frame 1 which may be of any height and width desired. Cross strips 2 which are preferably formed of metal extend transversely of the frame with their ends secured to the side bars 3 of the frame and certain of these cross strips are formed with openings 4 through which screws or other fasteners may be passed in order to secure the frame to the wall. These cross strips are spaced from each other vertically of the frame and it is to be understood that any suitable number may be employed. A head piece 5 having a glass at its front is mounted in the upper portion of the frame and in this head piece is mounted a sign 6 bearing removable letters forming the word "Directory", as shown at 7, the name of a building or any other heading desired. 55

Between the head piece and the lower end of the frame are disposed a number of name-carrying bars 8 which are disposed one upon another, as shown in Figure 3, and these bars fit against a sheet metal backing 9 which is disposed in the frame and secured against the front faces of the cross strips 2, as shown in Figures 1 and 2. The backing sheet is of appreciably less width than the frame and has one side portion bent to form a flange or cleat 10, and this flange is in its turn bent to 60 form a lip 11 which projects transversely from the flange or cleat towards a second flange or cleat 12 formed by bending the other side portion of the backing sheet. This flange may be bent back upon itself, as shown in Figure 2, in order to form it with a smooth forward edge and also permit a good binding action to take place when the cleat 12 is engaged in the transversely extending grooves 65

13 cut in the rear faces of the name-carrying bars of strips. Each name-carrying bar has one end bearing firmly against the flange or cleat 10 and is cut from this end to form a longitudinally extending groove 14 to receive the lip 11. Since the grooves 14 extend 70 transversely through the name-carrying bars, these bars may be slid vertically in the frame in order that a bar carrying the name of a new tenant may be set in place in its proper position and since the bars are readily 75

removable the name may be applied to a bar and this bar then set in place in its proper position in the frame. By this arrangement it is not necessary for a person to apply letters forming a tenant's name to a carrier mounted in the frame. By referring to Figure 2, it will be seen that the name-carrying bars are of such length that when they are engaged with the flanges or cleats of the 5 backing sheet their ends will be disposed in spaced relation to the side bars of the frame. It should also be noted that the backing sheet terminates at its top and bottom in spaced relation to the head 5 and the lower bar 15 of the frame. Therefore, a closure 16 consisting of an open frame and a transparent sheet of glass may be set in place within the main frame with its side bars fitting between ends of the name-carrying bars and the side bars 3 of the main frame and its upper and lower bars engaging between the backing sheet and the head 5 and lower bar 15 of the main frame. Tongues 17 project upwardly from the closure to engage back of the head 20 and the lower cross bar of the closure frame carries a latch 18 adapted to be engaged by a key and turned into and out of position to engage back of the lower bar 15 of the main frame and securely but releasably hold the 25 closure in place.

Each of the name-carrying bars is constructed as shown in Figure 4, and referring to this figure it will be seen that the front face of the bar has longitudinally extending 30 grooves formed therein. A facing 19 of fabric is glued or otherwise secured to the name bar and may have portions tucked into the grooves formed in the front face thereof or slits may be formed in the facing to register 35 with the grooves. By this arrangement letters 20 may be disposed against the front faces of the name-carrying bars with prongs 21 engaged in the slits of the bar and the letters will be firmly applied to the bar but 40 may be easily removed. The fact that the transparent sheet of the closure bears against the letters when the closure is in place will very effectively prevent danger of the letters accidentally slipping out of place.

When this directory is in use, it is secured 45 against a wall or other support by screws passed through the openings 4. Letters forming the names of tenants of the building are applied to the name-carrying bars and these bars set in place with their grooves 50 14 receiving the lip 11 of the flange or cleat 10 and the flange or cleat 12 engaged in the grooves 12 of the bars. The closure is then 55 set in place and secured by the latch 18 and since the transparent sheet of the closure bears against the letters they cannot accidentally slip out of place. When it is necessary 60 to apply the name of a new tenant, a blank name-carrying bar is removed and can be set 65 upon a desk while applying the necessary

letters. Therefore, the letters may be very easily applied and it will not be necessary for the attendant to stand upon a step ladder or other support while applying the name in case the sign is in an elevated position. By 70 shifting the name-carrying bars vertically in the frame space may be provided in order that the name of a new tenant may be applied in its proper position.

In Figure 5, there has been shown a modified construction. In this form of the invention the strips 2 are omitted and a backing sheet 22 substituted in place thereof. This backing sheet extends the full width of the frame and is secured against rear 75 faces of the side bars 3. Instead of employing a metal backing sheet 9 which has its side portions bent to form the cleats or flanges, there has been provided cleats 23 and 24 consisting of strips of angle metal. 80 These cleats are secured against the backing sheet 22 with their flanges 25 and 26 projecting outwardly or forwardly and the flange 25 carries a side flange or lip 27 corresponding to the lip 11. In other respects this form of 85 directory is the same as that previously described and the name-carrying bars are applied thereto in the same manner.

Having thus described the invention, I 90 claim:

1. A directory comprising a frame open at its front, a transparent closure for the front of said frame, a backing in said frame having cleats extending vertically therein in transverse spaced relation to each other and 100 each having an outstanding flange, one flange having a lip projecting towards the other cleat, and bars extending transversely in said frame to have characters applied thereto, said bars each having one end formed with a longitudinally extending seat to receive 105 said lip and being formed in its rear face with a transverse seat to receive the other cleat.

2. A directory comprising a frame open at its front, cleats extending vertically in said frame and projecting towards the open front thereof, said cleats being spaced from each other transversely of the frame and one having a longitudinally extending lip projecting transversely therefrom towards the other cleat, and name-carrying bars extending 110 transversely in said frame one above another and each having one end formed with a seat receiving the lip of the first cleat and its rear 115 face formed with a seat receiving the second cleat.

3. A directory comprising a frame open at its front, cleats extending vertically in said frame and projecting towards the open front thereof, said cleats being spaced from each other transversely of the frame and one having a longitudinally extending lip projecting transversely therefrom towards the other cleat, name-carrying bars extending 120

transversely in said frame one above another and each having one end formed with a seat receiving the lip of the first cleat and its rear face formed with a seat receiving the 5 second cleat, and a transparent closure for the open front of said frame retaining the bars in engagement with the cleats when in place.

4. A directory comprising a frame open 10 at its front, strips extending transversely of said frame, a backing sheet secured to said strips and having portions bent to form vertically extending flanges spaced transversely from each other and one flange being bent to 15 form a longitudinally extending side lip projecting towards the other flange, and name-carrying bars in said frame disposed one above another and formed with grooves receiving the lip and other flange to detachably 20 and slidably mount the bars.

5. A directory comprising a frame open at its front, strips extending transversely of said frame, a backing sheet secured to said strips and having portions bent to form vertically extending flanges spaced transversely from each other and one being bent to form a longitudinally extending side lip projecting towards the other flange, name-carrying bars in said frame disposed one above another 25 and formed with grooves receiving the lip and other flange to detachably and slidably mount the bars, and a closure having a frame fitting into the first frame and a transparent sheet bearing against front faces of the name-carrying bars.

6. A directory comprising a frame open at its front, name carrying bars extending transversely in said frame, one above another and having their rear faces provided with 40 seats, means to engage one end of each bar and prevent outward movement of the bars and means to engage the seats in the rear faces of said bars and prevent shifting of the same transversely in the frame.

45 7. A directory comprising a frame open at its front, cleats extending vertically in the frame and projecting towards the open front thereof, said cleats being spaced from each other transversely of the frame, and name carrying bars extending transversely in the frame, one above another and each having one end abutting one cleat, the rear faces of 50 the bars being formed with seats receiving the second cleat.

55 In testimony whereof I affix my signature.
RICHARD W. CLARK.
